UNITED STATES PATENT OFFICE.

ANTHONEY LETZKUS, OF PITTSBURG, PENNSYLVANIA.

VALVE-SADDLE FOR TAPPING WATER OR OTHER MAINS.

SPECIFICATION forming part of Letters Patent No. 390,490, dated October 2, 1888.

Application filed June 7, 1888. Serial No. 276,336. (No model.)

To all whom it may concern:

Be it known that I, ANTHONY LETZKUS, a citizen of the United States, residing at Pittsburgh, in the county of Allegheny and State of Pennsylvania, have invented new and useful Improvements in Valve-Saddles for Tapping Water or other Mains, of which the following is a specification.

This invention has for its objects to provide 10 a simple, durable, and efficient valve-containing saddle for drilling mechanism to tap water, gas, or other fluid mains without removing the fluid-pressure therefrom, and to provide novel means for connecting the saddle 15 with the main to be tapped.

The invention consists in a saddle for tapping mains divided horizontally into an upper and a lower section having side grooves forming a rectilinear internal valve-seat with a horizontally-sliding valve therein, the lower section having a semicircular bottom seat and formed integral with pairs of perforated lugs and the upper section having a sleeve for connecting with a drill mechanism and formed 25 integral with pairs of perforated lugs registering with those on the lower section, in combination with stirrups having rigid screw-threaded arms extending through the lugs, and screw-nuts on the arms for clamping the two 30 sections together and also binding the saddle bodily on the main to be tapped.

In the accompanying drawings, illustrating my invention, Figure 1 is a perspective view of the saddle-casing with the stirrups in place; 35 Fig. 2, a transverse sectional view showing the saddle-casing clamped on a main, as when the latter is to be tapped. Fig. 3 is a longitudinal sectional view of Fig. 1, and Fig. 4 a detail plan view of the disk-valve and its operating-stem.

In order to enable those skilled in the art to make and use my invention, I will now describe the same in detail, referring to the drawings, where it will be seen that the saddle-casing is divided on a horizontal line into an upper section, 1, and a lower section, 2, the opposite internal sides, 3, of which are provided with tapering grooves 4, which, when the sections are placed together in proper register, constitute a horizontal rectilinear valve-seat tapering from end to end of the casing.

The lower section, 2, is formed at its under-

side with a longitudinal cavity, arched in cross-section, and constituting a semicircular seat, 5, to fit upon the external surface of a gas, 55 water, or other fluid main, as in Fig. 2, and said lower section, 2, is also formed integral with a pair of lugs, 6, at each of its sides, each pair of lugs rising from and integral with a side flange, 7, which is likewise integral with 60 the lower section.

The upper section, 1, of the saddle-casing is formed integral with a pair of laterally-projecting lugs, 8, at each side, which register with those on the lower section, and through all of 65 the lugs are formed smooth vertical orifices, through which are passed the arms of two rigid stirrups, 9, adapted to encircle a main, as in Fig. 2, and having their extremities screw-threaded to receive screw-nuts 10, by 70 which the two horizontal sections of the saddle-casing are clamped together, and the entire casing also clamped with its semicircular seat upon the surface of the main to be tapped.

The upper section, 1, of the saddle-casing is formed integral with a sleeve, 11, having an internal screw-socket, 12, for the purpose of receiving and attaching the drill mechanism for tapping the main. I do not deem it necessary to here exhibit the drill and its appurtenances, as they may be of any known construction required. A suitable mechanism for this purpose is exhibited in Letters Patent, No. 174,542, issued to me March 7, 1876. If 85 such drill is used it will only be necessary to screw the drill-carrying tube shown in said patent into the screw-socket 12 of the sleeve 11 on the upper section, 1, of the saddle-casing. The disk-valve 13 is tapering to correspond to 90 the tapering valve-seat formed by the grooves 4, and this valve is movable in a horizontal plane below the screw-socket 12, and between the two sections comprising the saddle-casing. A screw-threaded valve stem, 14, working in a 95 screw-socket, 15, in one end of the saddle-casing, is swiveled at its inner end to the disk-valve, as at 16, Figs. 3 and 4, so that by turning the valve-stem the valve is adjusted across the sleeve and over the orifice 17 in the lower section, 2, of the casing, which orifice permits the passage of the drill to the main when the valve is properly adjusted for this purpose.

The lugs, rigid stirrups, and screw-nuts not

only provide simple and efficient means for clamping the saddle bodily on the main to be tapped, but also to connect and clamp the two sections of the saddle-casing together.

5 In practice, when a main is to be tapped the saddle is clamped thereupon by the rigid stirrups, as in Fig. 2, and the valve being in its open position the drill is operated through the screw-socket 12 and orifice 17. The top 10 having been formed, the drill is withdrawn and the valve-stem quickly turned to move the valve across the screw-socket 12 and close the valve. A plug or cock is then secured to the drill-rod, as in my aforesaid patent, the valve 15 is again opened and the plug or cock inserted into the tap, all as is ordinarily practiced in this class of apparatus.

What I claim is—

1. A saddle for tapping mains divided horizontally into an upper section and a lower section having registering side grooves forming a rectilinear valve-seat and a horizontally-sliding valve therein, the lower section having the semicircular bottom seat and formed integral with the pairs of perforated side lugs, and the upper section having a sleeve for connecting with a drill mechanism and formed integral with pairs of perforated side lugs registering with those on the lower section, in 25 combination with stirrups having rigid screw-threaded arms extending through the lugs, and screw-nuts on the arms for clamping the two sections together and also binding the saddle bodily on the main to be tapped, substantially 30 as described.

2. A saddle for tapping mains under pressure, divided horizontally into an upper and a lower section, having registering side grooves tapering from end to end and forming a recti-

linear tapering valve-seat, and a tapering disk- 40 valve moving horizontally in said seat between the two saddle-sections, the lower section having the semicircular bottom cavity to fit the main and formed integral with pairs of perforated side lugs, and the upper section having the sleeve and formed integral with the pairs of perforated side lugs, in combination with the stirrups having their rigid screw-threaded arms extending through the lugs, and screw-nuts on the arms for clamping the saddle-sections together, and also binding the saddle bodily on the main to be tapped, substantially 45 50 as described.

3. A saddle for tapping mains, divided horizontally into an upper and a lower section having internal grooves constituting a rectilinear valve-seat, the lower section provided with a through-orifice and a semicircular bottom seat and formed integral with pairs of vertically-perforated side lugs, and the upper section provided with a sleeve to connect with a drill and formed integral with vertically-perforated side lugs registering with those on the lower section, in combination with a disk-valve sliding horizontally between the sections, 55 the stirrups having their screw-threaded arms extending through the lugs, and the screw-nuts on the arms for clamping the two saddle-sections together, and also binding the saddle bodily on the main to be drilled, substantially 60 70 as described.

In testimony whereof I affix my signature in presence of two witnesses.

ANTHONEY LETZKUS.
